GAS TURBINE

Edward A. Stalker, Bay City, Mich.

Application March 12, 1945, Serial No. 582,395

13 Claims. (Cl. 170—135.24)

1 My invention relates to a combustion turbine prime mover for aircraft propulsion. An object is to provide means of achieving best performance for the turbine under all operating conditions.

Another object is to provide a means for controlling the relative rotational speeds of the rotors of any aircraft turbine having contra-rotating stages in order that best flow conditions can be approached at entrance to each stage under all operating conditions.

Another object is to provide a means for preheating the turbine blade cooling air in order that the turbine may operate at best efficiency allowed by the maximum working temperatures of the turbine blades. Other objects will appear from the description and drawings.

I accomplish the above objects by the means illustrated in the accompanying drawings in which—

Figure 1 shows an axial section of the turbine showing its various elements and control system;

Figure 1a is a chordwise section through the rotor blade of the first stage;

Figure 2 shows a combination of turbine vector diagrams;

Figure 3 shows a cross section of the automatic indicator mechanism for controlling the R. P. M. of the exit rotor taken in the plane of the paper;

Figure 4 is a fragmentary top view of the automatic indicator mechanism showing its various displacements; and

Figure 5 is fragmentary elevation of the electrical contactor system shown partly in section taken in the plane of the paper—for actuating the controls of the constant speed propeller governor.

It is a feature of this invention that two rotors of a gas turbine are run in opposite directions so as to extract sufficient of the energy of the gas in two stages to make the machine adequately efficient. It is a feature that these stages are coordinated through the control of the automatically controllable propellers and a mechanism responsive to the direction and velocity of the gas leaving the blades of the first stage.

One master propeller has its speed automatically regulated by a governor controlling the propeller pitch. The second propeller has a governor whose pitch is responsive automatically to the gas velocity and direction leaving the first rotor which drives the master propeller. The second rotor drives the other propeller.

Referring to Fig. 1, air enters the axial-flow compressor 2 by the annular entrance 4. The

5 compressed air leaves the compressor at exit 6 entering the precombustion chamber 8 from which a portion of the air passes through the burner 10 where it burns with the generated fuel entering the burner by a multiplicity of generation tubes 12. The remainder of the air passes through slots 14 where it mixes with the burned gases in mixing chamber 16. These hot gases are then passed through the air-cooled nozzles 18, then through the blades 20 of stage 1, thence through the contra-rotating blades 22 of stage 2 thence through the stator vanes 24, then through heat exchanger 26 (the purpose of which will be explained subsequently), then out exit 28, and finally are passed to the atmosphere around the air-cooled propeller-blade protector muffs 30.

10 The fuel system supplying fuel to the turbine generation tubes 12 is arranged as follows. A fuel pump 32 pumps fuel from tank 34 to the pilot's throttle control 35 via line 36. The throttle control 35 meters the fuel to the turbine by way of line 37.

15 1st stage rotor 40 drives shaft 42 which in turn drives the axial-flow compressor rotor 44 and the sun gear 46 of the propeller planetary gear drive 48 which in turn drives the constant speed propeller 50 by means of shaft 52. An accessory drive gear 54 is provided to drive the oil pump 56 and the constant speed governor 58.

20 Push-pull cable 60 connects the constant speed governor 58 to the pilot's speed control lever 62.

25 2nd stage rotor 70 running in a counter direction to 1st stage rotor 40 drives shaft 72 which in turn drives the sun gear 74 of the planetary gear drive 76 which in turn drives the constant speed propeller 78 by means of shaft 80. An accessory drive gear 82 is provided to drive the oil pump 84 and the constant speed governor 86. Push pull cable 88 connects the constant speed governor 86 to the automatic speed control mechanism housed in the control box 90.

30 35 This invention discloses a device to automatically control the 2nd stage rotational velocity so as to give best efficiency of operation for said 2nd stage under the several operating conditions of the 1st stage and thereby achieve best turbine efficiency.

40 45 Referring to Fig. 2, the solid lines represent a vector diagram for the turbine when running at design conditions. ab is the absolute velocity vector leaving nozzles 18. Adding in the blade speed vector bc gives the relative velocity vector ac with respect to the 1st stage rotor blades 20. Vector cd represents the relative velocity leaving blade 20.

When blade speed $de=bc$ is subtracted from cd there results absolute velocity vector ce at an angle ϵ from the axis of rotation. Adding in the blade velocity ef of the 2nd stage contra blades 22 gives the relative entering velocity vector cf at an angle α from the axis of rotation. Vector fg represents the relative leaving velocity. When blade speed $gh=ef$ is subtracted from fg there results an absolute velocity vector fh approaching stator vanes 24. The gases leave the stator vanes 24 in an axial direction giving velocity vector hj .

Considering the case where the pilot goes to a reduced throttle condition then if no correction has been made as to rotor speeds the propeller governor would allow the rotors to run at their former constant speed conditions and the vector diagram in Fig. 2 would be altered to that shown by the dashed (-----) vectors as follows: ab drops in value to kb ; ac changes to kc ; cd drops to cl ; $de=lm$; ce changes to cm ; $ef=mn$; cf changes to cn ; fg drops to no ; $op=gh$; fh changes to np ; and finally hj drops to pq . It will be noted that the change in angle of approach to 1st stage blades 20 amounting to ack is practically negligible as compared with the change of angle of approach fcn at entrance to the 2nd stage blades 22.

The 1st stage blades 20 would easily handle such a change in angle as ack but the 2nd stage off-design condition fcn entering blades 22 would be obviously inefficient and therefore requires a change in vector diagram in order to correct the angle of approach to something nearer the original angle α . The means of accomplishing this is to reduce the blade velocity from the value mn to the value mr , thus resulting in a relative approach velocity cr to blades 22 at the required angle α and giving a change in vector diagram as indicated by the double dashed (-----) vectors as follows: no changes to rs ; np changes to rt ; and finally pq changes to tu . Note that $st=mr$.

This invention discloses a device to automatically control the 2nd stage rotational velocity mr so as to give best efficiency of operation for any reasonable throttle setting or change in R. P. M. of the first rotor 40.

Fig. 3 shows a cross section of the automatic indicator mechanism, which in a simple way reproduces or simulates the absolute velocity vector in magnitude and direction as it leaves 1st stage rotor blades 20. This mechanism is located between blades 20 and 22 as shown in control box 90 of Fig. 1. The mechanism (Figures 1 and 3) consists of several elements, the main one being a streamlined vane 100 that indicates the absolute velocity direction leaving blades 20 and which is connected to the centrifugal indicator housing 102 by means of the hollow shaft 104 which is supported by bearings 106. The vane 100 contains a suitable duct 108 to direct a portion of the turbine gases past the small rotor 110 which drives sun gear 112 by means of shaft 114. Thus, rotor 110 drives the planet gears 116 around internal gear 118 attached to housing 102 at a rate directly proportional to the absolute velocity of the turbine gases leaving blades 20. The planet gears 116 drive the centrifugal indicator assembly 120 which is supported on the hollow slotted shaft 122 by bearings 124.

Assembly 120 is composed of lifter type centrifugal weights 126 pinned to clevis support 128 by pins 130 and operating actuator pin 132 by bearing on bar 134 sliding in slot 136. The actuator pin 132 is limited to a definite displacement by lever 138 attached to case 102 by pin 140 and spring 142. Lever 138 in turn actuates arm 144.

the end of which moves in the plane of vane 100 and actuates link 150 by means of ball-socket joint 152.

Fig. 4, which is a top view of the automatic indicator mechanism of Fig. 3, reveals the action of the mechanism in reproducing the pertinent portions of the vector diagram already mentioned in the explanation of Fig. 2. Thus, at design conditions, the rotor 110 drives the centrifugal lifter weights 126 at a rate sufficient to give a displacement X of the ball socket joint 152 at an angular displacement of ϵ from the turbine axis of rotation 153. At the previously mentioned off-design condition, at decreased throttle, the decreased absolute velocity vector cm in Fig. 2 evidences itself on the mechanism by indicating a displacement of magnitude Y at an angular displacement of β from the turbine axis of rotation 153. These displacements are combined to actuate the propeller speed governor 86 so as to achieve the required 2nd stage blade speed vector mr , in order to maintain a constant value for the relative entrance velocity vector angle α at the approach to blades 22. In Fig. 4, line 154 at an angle α to a plane through the center line of rotation, would be the locus of all positions of ball joint 152 that makes vector mr of Fig. 2 become zero. The actuator link 150 should be of sufficient length to maintain a substantially perpendicular position with respect to line 153 throughout the operative range in order to prevent secondary deviations. At design condition the ball joint 152 is located at a distance X from line 154 and at an off-design condition is located at a distance y . These distances correspond respectively to ev and mv of Fig. 2 which are respectively proportional to the 2nd stage blade speed vectors ef and mr at design and off-design conditions.

Referring to Fig. 5 it will be noted that link 150 is pinned to a double throw electrical contactor 155 mounted so as to freely slide axially in the Micarta support 156 attached to the female member of screw-jack 158. The screw-jack is actuated by an electric gear motor 160 having a pivot mounting 162. The gear motor is of the reversing type connected as shown in Fig. 5 to the two contacts 162 and 164 mounted on Micarta block 156. The screw-jack 158 is connected through an appropriate linkage system 166 to the push-pull control cable 88 which in turn is attached to the constant speed governor 86 as shown in Fig. 1. Therefore, any deviation in the flow system that will cause ball joint 152 to displace link 150 will cause contactor 155 to make circuit with either contact 162 or 164 and displace the screw-jack 158 to a point where the contactor 155 is no longer moving, then the electric circuit is broken with either contact 162 or 164, depending on the direction of travel, at which time the second stage constant speed governor 86 is automatically set at the correct R. P. M. to give the required blade speed vector mr in Fig. 2 to obtain the correct relative entering angle α to blades 22.

Each rotor blade is hollow and has in its surface one or more slots 87 as shown in Figure 1a through which air from 26 is passed into the turbine passage. However in the vector diagram of Fig. 2 the rotor and stator blades which are hollow have been shown solid for diagrammatic convenience. The air in passing out of the slot over the surface provides a protective layer of relatively cool air between the motive gas and the surfaces of the blades.

Because the protective air is at a high pressure within the blade, it has a significant drop in temperature when it expands through the slot. This lowers the temperature of the gas in the turbine passage 174 too much and it is desirable therefore to heat the gas some on its way to the blades by means of the heat exchanger 26. Thus a further improvement in efficiency is accomplished by preheating the cooling or protective air.

Referring to Fig. 1, air is bled off at annular port 170 of compressor 2 and transferred by means of the annular duct 172 to the entrance of the annular heat exchanger 26 located in the turbine passage 174. The cooling air passing through 26 absorbs heat from the exhaust gases so that the cooling air temperature is the maximum allowable to cool the blades. The air leaves the exchange 26 by means of duct 176 which delivers the air to the rotors 40 and 10 to be employed in cooling the blades in a similar fashion to that shown in my application S. N. 455,528, now abandoned.

It will now be clear that I have provided a simple and compact turbine of light weight and high efficiency.

I have now described suitable embodiments of my invention which are now preferred. It is to be understood however that the invention is not limited to the particular construction illustrated and described and that I intend to claim it broadly as indicated by the scope of the appended claims.

I claim:

1. In combination to form a gas turbine, two axial flow rotors having blades adapting them for rotation in opposite directions about a common axis, means mounting said rotors in spaced tandem relation for actuation by a common gas stream to rotate said rotors in opposite directions, an adjustable pitch propeller for each rotor and means operably connecting each propeller to its respective rotor for rotation thereby, and means to adjust the relative pitches of said propellers to adjust the rates of rotation of said rotors relative to each other, the last said means operating automatically in response to a change in the direction of said gas stream relative to said rotor.

2. In combination to form a gas turbine, two axial flow rotors having blades adapting them for rotation about a common axis, means mounting said rotors in spaced tandem relation for actuation by a common gas stream to rotate said rotors in opposite directions, an adjustable pitch propeller for each rotor and means operably connecting each propeller to its respective rotor for rotation thereby, and means to adjust the relative pitches of said propellers to adjust the rates of rotation of said rotors relative to each other, the last said means operating automatically in response to a change in the direction of said gas stream.

3. In a combination to form a gas turbine, two rotors having blades adapting them for rotation in opposite directions, means mounting said rotors for actuation by a common gas stream rotating said rotors in opposite directions, an adjustable pitch propeller for each rotor and means operably connecting each propeller to its respective rotor for rotation thereby, and means to adjust the relative pitches of said propellers to adjust the rates of rotation of said rotors relative to each other, the last said means operating

automatically in response to the direction of the gas flow leaving one rotor.

4. In combination to form a gas turbine, two rotors having blades adapting them for rotation in opposite directions, means mounting said rotors for actuation by a common gas stream rotating said rotors in opposite directions, an adjustable pitch propeller for each rotor and means operably connecting each propeller to its respective rotor for rotation thereby, and means to adjust the relative pitches of said propellers to adjust the rates of rotation of said rotors relative to each other, the last said means operating automatically in response to the direction and magnitude of the velocity of the gas flow leaving the upstream rotor.

5. In combination, in a gas turbine, a plurality of turbine rotors having blades, two of said rotors having oppositely directed blades to cause rotation in opposite directions, a shaft for each of said rotors fixed thereto, means for mounting said shafts and rotors for rotation in opposite direction under the motive action of a gas, means to supply a gas flow through the blades of said rotors to rotate them, an adjustable pitch propeller for each said shaft adapted to be driven by its respective shaft, a governor to regulate the speed of rotation of one of said propellers in a prescribed manner, and means to regulate the pitch of the second said propeller in response to the absolute velocity and direction of the gas flow passing from the first said rotor to the second said rotor whereby to provide a proper approach of the gas to said second rotor.

6. In combination, in a gas turbine, a plurality of turbine rotors having blades, two of said rotors having oppositely directed blades to cause rotation in opposite directions, a shaft for each of said two rotors fixed thereto, means for mounting said shafts and rotors for rotation in opposite direction under the motive action of a gas, means to supply a gas flow through the blades of said rotors to rotate them, an adjustable pitch propeller for each said shaft adapted to be driven by its respective shaft, a governor to regulate the speed of rotation of one of said propellers in a prescribed manner, and means to regulate the pitch of the second said propeller in response to the absolute velocity of the gas flow passing from the first said rotor to the second said rotor whereby to provide a proper approach of the gas to said second rotor.

7. In combination, in a gas turbine, a plurality of turbine rotors having blades, two of said rotors having oppositely directed blades to cause rotation in opposite directions, a shaft for each of said two rotors fixed thereto, means for mounting said shafts and rotors for rotation in opposite direction under the motive action of a gas, means to supply a gas flow through the blades of said rotors to rotate them, and means to govern the relative speeds of said two rotors as a function of the velocity and direction of the gas leaving one of said rotors for flow to the second rotor, whereby to provide a proper angle of approach of the gas flow to said second rotor.

8. In combination in a gas turbine, two rotors having blades, said rotors being adapted to rotation in opposite directions, means mounting said rotors for actuation by a common gas stream rotating said rotors in opposite directions, an adjustable pitch propeller operably connected to one of said rotors, another power absorbing device operably connected to the other said rotor, and means responsive to the direction of the

turbine gas stream to adjust the pitch of said propeller to coordinate the relative rate of rotation of said rotors.

9. In combination in a gas turbine, two rotors having blades, said rotors being adapted to rotation in opposite directions, means mounting said rotors for actuation by a common gas stream rotating said rotors in opposite directions, an adjustable pitch propeller operably connected to one of said rotors, another power absorbing device operably connected to other said rotor positioned ahead of the first said rotor, and means responsive to the velocity of the turbine gas stream aft of the rotor coupled to said device to adjust the pitch of said propeller to coordinate the relative rates of rotation of said rotors.

10. In combination in a gas turbine, two rotors having blades, said rotors being mounted for independent rotation by a common gas stream, a power absorbing device operably connected to a said rotor, a means for inducing a flow of air operably connected to another said rotor, and means adjacent a said rotor responsive to a change in the peripheral direction of the said gas stream relative to the last said rotor to adjust the rate of airflow through said means for inducing a flow to coordinate the relative rate of rotation of said rotors.

11. In combination in a gas turbine, two rotors having blades, said rotors being mounted for independent rotation by a common gas stream, a heating means having a fuel burner for the introduction of fuel thereinto to heat said stream, a power absorbing device operably connected to a said rotor, a means for inducing a flow of air operably connected to another said rotor, and means responsive to the rate of flow of the said gas stream between said fuel burner and a said rotor to adjust the rate of airflow through said means for inducing a flow to coordinate the relative rate of rotation of said rotors.

12. In combination in a gas turbine, a rotor having blades, means mounting said rotor for

actuation by a gas stream, heating means having an inlet to receive said stream therethrough, said heating means being adapted to heat said stream enroute to said rotor, an adjustable pitch propeller operably connected to said rotor, and means responsive to the velocity of the turbine gas stream to adjust the pitch of said propeller, said responsive means being positioned downstream from said inlet and upstream from said rotor.

13. In combination in a gas turbine, a set of axial flow blades mounted in peripherally spaced relation to direct a gas stream therethrough, a rotor having a set of axial flow blades therein, said rotor being mounted for rotation about an axis by said gas stream downstream from the first said set of blades, a means for inducing a flow of air operably connected to said rotor to be driven thereby, and means responsive to the rate of flow of said gas stream to adjust the rate of flow of said means for inducing, said responsive means being positioned between said sets of blades.
